UNITED STATES PATENT OFFICE.

CHARLES H. THARP, OF CHICAGO, ILLINOIS, ASSIGNOR TO SEARS, ROEBUCK AND CO., OF CHICAGO, ILLINOIS, A CORPORATION OF NEW YORK.

GARMENT-HOLDING FORM.

1,317,241.

Specification of Letters Patent. Patented Sept. 30, 1919.

Application filed May 29, 1919. Serial No. 300,698.

To all whom it may concern:

Be it known that I, CHARLES H. THARP, a citizen of the United States, residing at Chicago, in the county of Cook and State of Illinois, have invented certain new and useful Improvements in Garment-Holding Forms, of which the following is a specification.

This invention relates to improvements in garment holding forms, and the main object of this invention is to provide a packing device which can be used by mail order houses and other dealers in clothing in packing men's suits and overcoats for shipment to the purchaser.

Another object is to provide a garment form of improved construction which may be stored in a flat condition and assembled ready for use in a short time.

The invention consists generally of a flat substantially rectangular sheet of suitable material, preferably cardboard or fiberboard, having two flaps adapted to form thickened shoulder pads for the garment. A hanging tab is also provided at the top of the form for hanging up said form.

In the drawings, Figure 1 is a plan view of the form in flat condition. Fig. 2 is a plan view of the device in operative form. Fig. 3 is a fragmentary perspective rear view of the flap-fastening means, and Fig. 4 is a fragmentary sectional view taken on line 4—4 of Fig. 2.

Referring more particularly to the drawings, 1 represents a sheet of material preferably cardboard or fiberboard, of which the form is made. A pair of flaps 2 are preferably formed at the upper corners of the body 1. At the junction of the flaps 2 and the body portion 1, is preferably formed a sloping crease or indentation 3. Said crease or indentation extends from the upper outer corner of the body portion 1 to the bottom inner edge of said flap. (See Fig. 1). On the upper portion of the flap 2 is preferably formed a locking tongue 4, said tongue being adapted to fit into locking engagement with the substantially oblique slit 5 formed in the body 1 below said flap. Said oblique slit 5 is preferably sloped upwardly toward the vertical axis of the form 1.

The outer edge of the flap 2 curves outwardly between the outer end of the sloping crease 3 and the hook of the locking tongue 4, as at 6, so that when said flap 2 is folded

down over the body 1, a shoulder pad of ample size will be formed. When the form is in flat condition, the inner edge 7 of the flap 2 preferably lies in substantially the same plane as the vertical axis of the form, 60 and thus when the flap 2 is folded down over the body 1, the edge 7 lies substantially close to the body 1 so that the downward slope of the shoulder pad is gradual from its outer to its inner side. 8 is a substantially semi-circular slit in the flap 2 forming a tongue 9. The tongue 9 is bent upwardly at substantially right angles to the flap 2 so that when said flap is folded down over the body 1, said tongue 9 will project downwardly toward the body 1.

At a suitable distance below the crease or indentation 3, the body is provided with a substantially semi-circular slit 10 forming a tongue 11, said tongue being caused to 75 assume a vertical position with reference to the body 1 when the flap 2 is folded down over the body 1.

A neck tab 12 is preferably provided between the flaps 2, and at 13 is formed an 80 aperture by means of which the form may be hung up. A suitable distance below the oblique slits 5, a transverse slot 14 is provided through which slot trousers may be suspended.

In assembling the device into operative form, each of the flaps 2 is bent forward slightly along the indentation or crease 3; the tongue 9 is bent upwardly, so as to lie substantially at right angles to the flap 2; and the tongue 11 is bent upwardly so as to lie at substantially right angles to the body 1. The flap 2 is then bent down over the body 1 the locking tongue 4 is caused to engage with the slot 5. The projection 15 acts as 90 a stop lug for said tongue and limits the insertion of said locking tongue into the slit 5. (See Fig. 2). The tongue 11, lying at right angles to the body 1, partially fits into the aperture formed by the tongue 9 for 95 the reason that said tongue 11 is larger than the aperture formed by the tongue 9, and acts as a support for the shoulder pad. The tongue 9, because of the turning down of the flap 2, projects downwardly behind 100 the tongue 11, so that said tongue 11 is held against lateral displacement by the tongue 9 on one side and on the opposite or outer side by the aperture formed by the tongue 9. Upward or downward move- 110

ment is prevented by the locking tongue 4 and the stop lug 15 which are engaged in the oblique slit 5.

It will be seen that I have provided a garment form made of cheap material which may be stored in a flat condition and can be prepared for use at a moment's notice. Also the method of forming the thickened shoulder pad and holding the pad in a substantially rigid position is novel and advantageous.

I claim as my invention:

1. A device of the character described comprising a body portion, a flap foldable thereover to form a thickened garment shoulder pad, said flap having a locking tongue at its upper edge adapted to engage in a slit formed in the body portion, and means formed on the body portion and flap respectively, arranged to act as a support for the flap.

2. A device of the character described, comprising a body portion, a flap portion foldable thereover to form a thickened garment shoulder pad, said flap portion being adapted to be secured to the body portion, and a tongue formed on one of said portions and adapted to operatively engage with the other of said portions to support said shoulder pad in raised position with reference to the body portion.

3. A device of the character described, comprising a body portion, a flap foldable thereover to form a thickened garment shoulder pad, said flap having a locking tongue at its upper edge adapted to engage in a slit formed in the body portion, and a tongue formed in the body portion adapted to engage in a slot formed in said shoulder pad for supporting said shoulder pad.

4. A device of the character described, comprising a body portion, a flap foldable thereover to form a thickened garment shoulder pad, a locking tongue formed on the upper end of said flap, an oblique slit formed in the body to receive said locking tongue, a stop lug formed on said locking tongue and adapted to limit insertion of said locking tongue, and two tongues formed on the body and the flap respectively, ar-

ranged to co-act, and in conjunction with the locking tongue and stop lug hold said shoulder pad as a whole against movement.

5. In a device of the character described, a body portion formed of sheet material, a neck tab, two shoulder-pad-forming flaps located at either side of the neck tab, locking tongues carried by said flaps and adapted to engage in oblique slits formed in the body portion, lugs formed on said flaps adapted to limit insertion of the shoulder-pad-forming flaps into said oblique slits, a tongue formed on the body portion and a second tongue formed on the flap, said tongues being adapted to co-act when said flaps are folded down over the body, said co-acting tongues holding the shoulder-pad thus formed in a raised and fixed position with reference to the body.

6. In a device of the character described, a body portion formed of sheet material, a neck tab, two shoulder-pad-forming flaps located at either side of the neck tab, locking tongues carried by said flaps and adapted to engage in oblique slits formed in the body portion, lugs formed on said flaps adapted to limit insertion of the shoulder-pad-forming flaps into said oblique slits, a locking tongue formed near the outer edge of said shoulder-pad-forming flaps, and a substantially larger locking tongue formed on the body portion, both of said tongues lying substantially in the same plane, a substantial portion of the second mentioned tongue being adapted to engage in the aperture formed by the first mentioned tongue, the first mentioned tongue serving to hold the second mentioned tongue in the aperture formed by the first mentioned tongue.

7. A device of the character described comprising a body portion, a flap foldable thereover to form a thickened garment shoulder pad, means adapted to secure the flap to the body portion, and means formed integral with the body portion adapted to support the flap at approximately the central part thereof in raised position with reference to the body portion.

In testimony whereof, I have hereunto set my hand.

CHARLES H. THARP.
